UNITED STATES PATENT OFFICE.

THOMAS A. BRYAN, OF BALTIMORE, MARYLAND.

VALVE MECHANISM.

SPECIFICATION forming part of Letters Patent No. 651,230, dated June 5, 1900.

Application filed April 1, 1895. Serial No. 544,080. (No model.)

To all whom it may concern:

Be it known that I, THOMAS A. BRYAN, of Baltimore city, in the State of Maryland, have invented certain new and useful Improvements in Valve Mechanism; and I do hereby declare the following to be a full, clear, and exact description of the invention, such as will enable others skilled in the art to which it appertains to make and use the same.

My invention relates to an improvement in valves for the burners of gas-stoves.

The invention consists in certain novel features of construction and combinations and arrangements of parts, as hereinafter set forth, and pointed out in the claim.

The accompanying drawing represents a sectional view of a valve mechanism embodying my improvements and showing the application of the same to a burner.

The casing of my improved valve mechanism comprises two arms A B, disposed at right angles to each other and each having a longitudinal bore, constituting a chamber, which terminate, respectively, in valve-seats a b, with contracted outlets a' b', the walls of said valve-seats being made conical for the accommodation of the pointed ends of needle-valves A' B', which coöperate therewith. The outer end of the arm A of the casing is provided with a cap c, having a hole for the passage of the needle-valve A', and the latter is provided with screw-threads a², adapted to mesh with similar threads a³, made in the bore of the arm A of the casing. The needle-valve B' is adapted to project beyond the lower end of the arm B of the casing and in its lower end is made with a slot b² for the reception of a screw-driver or key. The valve B' is also provided with screw-threads b³, adapted to mesh with threads b⁴ on a sleeve b⁵, secured within the bore of the arm B. The upper or outlet end of the arm B is preferably provided with a tip d, adapted to discharge into the tube e of a burner C. The upper end of the arm B is also preferably screw-threaded externally, as at f, for the reception of the lower end of the burner-tube, and the latter is provided with a series of perforations g for the admission of air. The arm A of the casing is made with a perforated boss or inlet h, from which a threaded thim-

ble i projects for the attachment of the service-pipe.

From the construction and arrangement of parts above described it will be seen that the bore of the arm B communicates with the bore of the arm A and that the main supply of gas will enter the bore of the arm A through the inlet h and then pass through the outlet a' into the bore of the arm B, the admission of the gas to the bore of the arm B being controlled by the valve A'. From the bore or chamber of the arm B the gas will pass through the outlet b' to the burner; but the quantity and pressure of the gas as it passes through said outlet b' will be regulated by means of the valve B'. The valve B' can be set or adjusted for a certain pressure of gas to the burner and permitted to remain so set or adjusted indefinitely, the starting and stopping of the supply of gas being then controlled entirely by means of the valve A'. The constant supply of gas in the chamber B will tend to cause a steady exit of the gas from said chamber to the burner; but if this chamber were connected directly with the main the fluctuations of pressure in the latter would be transmitted through the chamber and cause unsteady feed of gas to the burner, resulting in the imperfect operation of the latter. To avoid such fluctuations of pressure in the main being transmitted through the chamber B and ultimately to the burner, I have provided the enlarged chamber A, which is connected directly with the main, and the accumulated gas in this chamber flows directly into the chamber which supplies the burner through a contracted outlet. Thus the fluctuations of pressure in the main are compensated for or absorbed by the body of gas in the enlarged chamber A and the gas passes from said chamber through the contracted outlet at a' into the chamber B at or nearly at a uniform pressure. Any slight fluctuations, however, in pressure of the gas entering the chamber B will be compensated for by the body of gas in the latter chamber and the uniformity of pressure of gas as it passes to the burner will be insured. In other words, the chamber A, with its contracted outlet, serves as a compensatory means for effecting the absorption of fluctuations of pressure in the main, and the cham-

ber B, with its contracted outlet, serves to prevent fluctuations of pressure of gas as it passes to the point of consumption.

My improvements are exceedingly simple 5 in construction, are applicable to any gas-burner, can be cheaply manufactured, and are effectual in all respects in the performance of their functions.

Having fully described my invention, what 10 I claim as new, and desire to secure by Letters Patent, is—

In a valve mechanism, the combination of 15 a chamber having a contracted outlet to supply gas therefrom to a burner, a valve to control the passage of gas through said outlet, an enlarged chamber having a contracted out-

let to communicate directly with the first-mentioned chamber, and a valve for said outlet, said enlarged chamber having an inlet adapted for direct connection with a supply pipe or main, whereby fluctuations of pressure in the supply pipe or main will be compensated for in one of said chambers and fluctuations of pressure to the burner will be compensated for in the other chamber. 20

In testimony whereof I have signed this specification in the presence of two subscribing witnesses. 25

THOMAS A. BRYAN.
